(57) **CLAIM**

We claim the ornamental design for a vehicle body exterior, as shown and described.

DESCRIPTION

FIG. 1 is a front view of a vehicle body exterior; FIG. 2 is a perspective view of the vehicle body exterior taken from the front;

FIG. 3 is a left side view of the vehicle body exterior;

FIG. 4 is a top view of the vehicle body exterior;

FIG. 5 is a perspective view of the vehicle body exterior taken from the rear; and,

FIG. 6 is a rear view of the vehicle body exterior.

In the drawings, the portions shown by broken lines form no part of the claim, and the right side view of the vehicle body exterior is omitted because the right side view is identical to the left side view except that the right side view does not have a gas cap cover as shown by broken lines in the left side view.
